UNITED STATES PATENT OFFICE.

EUGENE C. HERTEL, OF CHICAGO, ILLINOIS, ASSIGNOR TO SINCLAIR REFINING COMPANY, OF NEW YORK, N. Y., A CORPORATION OF MAINE.

ART OF CRACKING HYDROCARBON OILS.

Application filed January 12, 1928. Serial No. 246,263.

This invention relates to the cracking of higher boiling hydrocarbon oils, such as gas oil, for the production of lower boiling oils, such as gasoline or gasoline-containing oils, 5 by distillation under superatmospheric pressure; more particularly the invention relates to improvements in apparatus for carrying out pressure distillation cracking operations.

The apparatus of the present invention is 10 of special value and application in connection with an improved process of cracking hydrocarbon oils described and claimed in an application copending herewith filed January 12, 1928, Serial No. 246,262.

15 One form of apparatus embodying the invention is illustrated in the accompanying drawings. The accompanying drawings diagrammatically and conventionally represent a pressure still system, in elevation and partly 20 in section with parts broken away, embodying the invention.

Referring to the drawings, the pressure still system illustrated comprises a battery of heating tubes 2 arranged in the heating flue 25 of a furnace 3, a vaporizing drum 4, circulating connections, 5, 6 and 7 including a pump or other suitable forcing means 8, these connections and the forcing means being arranged for circulating oil from the vaporizing 30 drum upwardly through the heating tubes and back to the vaporizing drum, a valve 9 for closing the connection between the vaporizing drum 4 and the intake side of the forcing means 8, a reflux tower 10 with 35 vapor connections 11 and reflux return connections 12 to the still proper, a connection 13 for introducing raw oil into the reflux tower 10, a condenser 14, a receiver 15, and a connection 16 for discharging unvaporized 40 oil from the vaporizing drum 4. Connection 17 is provided for discharging the distillate product and connection 18 for discharging uncondensed vapors and gases from receiver 15. Pressure in the system may be 45 maintained and regulated by means of valve 19 in the vapor line 20 between the reflux tower 10 and the condenser 14, or by means of suitable valves arranged beyond the condenser or receiver. Connection 21 is provided for 50 initially charging the still at the beginning of a run and for pumping out the still at the end of a run. Connection 22 is provided for supplying cool oil, for example, cool raw oil 55 to be supplied to the still system, to or through the bearings of the forcing means 8. Con-

nnections 23, including suitable forcing means, are provided for recirculating over the heating tubes a portion of the heating gases which have passed thereover, as described in Letters Patent No. 1,574,546 and No. 1,574,547 issued 60 to the Sinclair Refining Company February 23, 1926, on applications of John E. Bell.

The connection 5 for circulating oil from the vaporizing drum 4 to the heating tubes 2 opens upwardly into the vaporizing drum 65 below the normal liquid level therein. The valve proper is arranged at the upper end of this connection. The form of valve illustrated, which is particularly advantageous, comprises a conical closure member arranged 70 to seat in the circular opening between the vapor-vaporizing drum 4 and the circulating connection 5. For raising and lowering the conical member 9, an operating extension 24 is attached thereto and carried through the 75 wall of the vaporizing drum through a stuffing box 25 arranged above the normal liquid level, the operating extension passing upwardly through the vaporizing drum and through the vapor space therein. The operating extension 24 is, with advantage, rigidly fixed to the closure member 9 so that all parts 80 of the valve mechanism exposed to high temperatures and hot oil in the still are of extreme simplicity. After passing through the 85 stuffing box 25, the operating extension 24 may be carried by a threaded yoke or any other suitable means for raising and lowering the closure member of the valve from and to the seat. With this arrangement, none of 90 the operating parts of the valve mechanism moving with respect to each other are exposed to high temperatures or hot oil in the still, excepting the closure member and seat and the inside of the stuffing box through which 95 the operating extension passes. This exposed portion of the stuffing box, moreover, is exposed only to the vapors within the still which are of relatively low heat capacity as compared to the liquid oil therein and which 100 are free from suspended solids or semi-solids.

The reflux return connections 12 open into 105 circulating connection 5 between valve 9 and the intake side of the forcing means 8. With this arrangement the change from circulation of admixed reflux condensate and unvaporized oil from the vaporizing drum through the heating tubes to circulation of reflux condensate therethrough without admixture of unvaporized oil from vaporizing drum or 110

vice versa can be made simply by closing or opening respectively valve 9. In the apparatus illustrated, raw oil introduced into the reflux tower 10 through connection 13 5 leaves the reflux tower through connection 12 and enters the circulating connection 5 in admixture with reflux condensate from the reflux tower.

In one way of operating the apparatus of 10 the invention, after an initial charge of oil is brought to cracking conditions of temperature and pressure, the still charge is during an initial period of operation circulated and recirculated through the heating tubes from 15 and to the vaporizing drum and in a subsequent period of operation the recirculation of unvaporized oil from the vaporizing drum is stopped and only reflux condensate or raw oil or admixed raw oil and reflux condensate 20 is circulated through the heating tubes to the vaporizing drum, the change in operation between this initial and this subsequent period being effected by closing the valve 9. The apparatus of the invention, however, is generally useful in operations in which this 25 change or the reverse change, or both, is to be made.

The invention is specifically described 30 therein with reference to the particular form of apparatus illustrated in the accompanying

drawings, but it is intended and will be understood that this detailed illustration is for the purpose of exemplification rather than limitation.

I claim:

A pressure still system comprising a vaporizing drum and a battery of heating tubes, a connection opening upwardly into the vaporizing drum below the normal liquid level therein for circulating oil from the vaporizing drum to the heating tubes, a forcing means in said connection, a connection for circulating oil from the heating tubes to the vaporizing drum, a reflux tower and vapor connection between the same and the vapor space of the vaporizing drum, a valve arranged at the upper end of said first mentioned connection and an operating extension therefor extending upwardly through the vaporizing drum and through the vapor space 50 within the same and passing through the wall of the vaporizing drum above the normal liquid level therein, and a reflux return connection from the reflux tower opening into said first mentioned connection between said 55 valve and said forcing means.

In testimony whereof, I have subscribed my name.

EUGENE C. HERTHEL.
